[57] ABSTRACT

Apparatus is disclosed for encoding a binary signal which takes on one or the other of first and second states during each of a plurality of T second intervals into a frequency modulated coherent phase-shift keyed signal which undergoes first and second phase deviations, respectively, during the T second intervals in which the binary signal is in its first and second states. More particularly, such encoding is accomplished by combining a cosinusoidal carrier signal, which has been amplitude modulated by a cosinusoidal signal of frequency $\frac{1}{4}T$, with a sinusoidal carrier signal, which has been amplitude modulated by a sinusoidal signal also of frequency $\frac{1}{4}T$, after the two amplitude modulated carrier signals have been inverted in polarity during first and second groups, respectively, of T second intervals of the binary signal.

APPARATUS FOR ENCODING A BINARY SIGNAL INTO A FREQUENCY MODULATED COHERENT PHASE-SHIFT KEYED SIGNAL

BACKGROUND OF THE INVENTION

This invention relates to the encoding of digital signals into coherent phase-shift keyed signals and, in particular, to arrangements which can provide such encoding for high information rate digital signals.

It is known in the prior art to encode a binary signal which takes on one or the other of first and second states during each of a plurality of T second intervals into a frequency modulated coherent phase-shift keyed (FM-CPSK) signal. The latter signal is a constant amplitude, continuous phase coherent carrier signal which undergoes first and second phase changes or deviations during the T second intervals in which the binary signal takes on its first and second states, respectively. The first and second phase deviations of the FM-CPSK carrier signal thus are the encoded form of the first and second states of the binary signal.

Prior art arrangements for providing such encoding of a binary signal into a FM-CPSK signal, typically, require the use of digital circuitry, such as counter circuits or clock circuits, which must operate at speeds in excess of the information rate of the binary signal. As a result the aforesaid prior art arrangements are capable of encoding only binary signals having relatively slow information rates. It is therefore a primary object of the present invention to provide an arrangement which can encode high speed binary signals into FM-CPSK signals.

SUMMARY OF THE INVENTION

In accordance with the principles of the present invention, a binary signal which takes on one or the other of first and second states during each of a plurality of T second intervals, beginning with a first interval, is encoded into an FM-CPSK signal which undergoes first and second phase deviations during the T second intervals in which the binary signal is in its first and second states, respectively, by combining a cosinusoidal carrier signal, which has been amplitude modulated by a cosinusoidal signal of frequency $\frac{1}{4}T$, with a sinusoidal carrier signal, which has been amplitude modulated by a sinusoidal signal of the same frequency $\frac{1}{4}T$, after the two amplitude modulated carriers have been inverted in polarity during preselected groups of T second intervals of the binary signal.

More specifically, after being generated, the amplitude modulated cosinusoidal and sinusoidal carrier signals are applied, respectively, to first and second polarity control circuits, both of which have two modes of operation, an invert mode of operation and a non-invert mode of operation. Each of these circuits, in turn, receives a direction at the beginning of each T second interval of the binary signal, as to whether it should or should not switch from its present mode of operation to its other mode of operation. When the binary signal is not undergoing a change in state at the beginning of a particular interval, both circuits are directed to maintain their present modes of operation. When the binary signal is undergoing a change in state, however, then one or the other of the circuits is directed to switch its operating mode. More specifically, when the particular interval being begun is an odd interval, then the second circuit is directed to switch

modes and the first circuit not to switch modes. When the interval is even, on the other hand, then the first circuit is directed to switch and the second circuit not to switch.

5 Operation of the first and second polarity control circuits in the aforesaid manner results in both the cosinusoidal and sinusoidal carrier signals being inverted or both being non-inverted during each T second interval in which the binary signal is in its first state 10 and results in either one or the other of the signals being inverted during intervals in which the binary signal is in its second state. As a result, combining the two carriers, after they have been selectively inverted by the first and second control circuits, produces a constant amplitude cosinusoidal signal having a first frequency and, hence, a first phase deviation, during each of the former T second intervals and second frequency and, thus, second phase deviation during each of the latter T second intervals. Moreover, due to the manner 15 in which the polarity control circuits have been switched, the resultant cosinusoidal signal is found to be continuous in phase when going from one T second interval to the next. Combining of the polarity-inverted amplitude modulated cosinusoidal and sinusoidal carriers thus results in a continuous phase constant amplitude cosinusoidal signal whose two phase deviations correspond to the two states of the binary signal and, hence, a resultant FM-CPSK signal.

DESCRIPTION OF THE DRAWINGS

A clearer understanding of the above-mentioned features of the present invention can be obtained by references to the following detailed description taken in conjunction with the following drawings, in which:

35 FIG. 1 shows an apparatus for generating a FM-CPSK signal, in accordance with the principles of the present invention;

FIGS. 2-9 illustrate various signals in the apparatus of FIG. 1;

40 FIG. 10 shows particular circuitry which can be employed in the apparatus of FIG. 1; and

FIGS. 11-12 illustrate various signals in the circuitry of FIG. 10.

DETAILED DESCRIPTION

In FIG. 1, a binary signal generator 11 generates a binary information signal b_{if} which takes on either one or the other of first and second states during each of a plurality of T second intervals. In FIG. 2, eight T second intervals of the signal b_{if} are illustrated. As shown, the signal takes on its first state, represented by a positive going pulse and designated a 1 state, during each of the T second intervals 1, 3, 4 and 7, and its second state, represented by a negative going pulse and designated a 0 state, during each of the intervals 2, 5, 6 and 8.

The binary signal b_{if} is to be encoded by apparatus 12 into a FM-CPSK signal having first and second phase deviations which represent the encoded forms of the first and second states, respectively, of the signal b_{if} .

60 More particularly, apparatus 12 comprises a carrier signal generator 13, which operates in synchronism with generator 11, to develop an amplitude modulated coherent cosinusoidal carrier signal C_c and an amplitude modulated coherent sinusoidal carrier signal C_s . The generated signal C_c is at a carrier frequency f_c and is amplitude modulated by a cosinusoidal modulating signal M_c which is at a modulating frequency of $\frac{1}{4}T$.

The generated signal C_s is also at a carrier frequency f_o and is amplitude modulated by a sinusoidal modulating signal M_s which is at the same modulating frequency as M_c .

In FIGS. 3 and 4, respectively, the signals C_c and C_s are illustrated in solid line. As shown, the frequency f_o of the signals is an integer multiple of $1/T$ and, in particular, is equal to $4/T$. Also illustrated in FIGS. 3 and 4 in broken line are the modulating signals M_c and M_s , respectively.

As can be observed from the aforesaid figures, the modulating signals M_s and M_c , since they are both at a frequency $\frac{1}{4}T$, cause the carrier signals C_s and C_c to be at zero amplitude at the beginning of each odd and each even interval, respectively, of the binary signal b_{if} . Thus, the sinusoidal carrier signal C_s is at zero amplitude at the beginning of a first set of alternate intervals (i.e., the odd intervals 1, 3, 5 and 7) of the signal b_{if} , while the cosinusoidal carrier C_c is at zero amplitude at the beginning of the second set of alternate intervals, interleaved between the first set of intervals, (i.e., the even intervals 2, 4, 6 and 8) of the signal b_{if} . The significance of the aforesaid behavior exhibited by the signals C_s and C_c will become clear from the discussion to follow.

The signals C_c and C_s are coupled from their respective generator 13 into carrier signal input ports 14 and 15, respectively, of two similar invert non-invert circuits 16 and 17. Each of the circuits 16 and 17 has two modes of operation, an invert mode of operation and a non-invert mode of operation. In the invert mode of operation, each circuit ideally produces an output whose amplitude is the same as that of the applied carrier signal at the carrier input port of the circuit, but whose polarity is opposite to that of such input signal. In the non-invert mode of operation, on the other hand, each circuit ideally produces an output identical in both amplitude and polarity to the applied carrier signal.

The circuits 16 and 17 are caused to be in one or the other of their respective modes of operation by applying control signals to the circuits. In particular, control signal b_{c1} is applied to control signal input port 18 of circuit 16 and control signal b_{c2} is applied to control signal input port 19 of circuit 17. The control signals b_{c1} and b_{c2} , in turn, are generated by a control signal generator 21 which operates in response to the binary signal b_{if} .

In accordance with the invention, the control signals b_{c1} and b_{c2} are generated by generator 21 such that the circuits 16 and 17 controlled thereby operate to selectively invert their respective applied carrier signals C_c and C_s to produce two partially inverted carrier signals C_c' and C_s' , respectively, which when combined in combiner 22 result in a resultant carrier wave C_r which is at a first frequency, and thus undergoes a first phase deviation, during each T second interval in which the binary signal b_{if} is in its first state and which is at a second frequency, and thus undergoes a second phase deviation, during each T second interval in which the signal b_{if} is in its second state. Moreover, in further accord with the invention, the signals b_{c1} and b_{c2} are generated such that the control exercised thereby over circuits 16 and 17 is such as to cause the aforesaid resultant signal C_r to have a continuous amplitude and thus a continuous phase at the transitions between adjacent T second intervals of b_{if} .

More specifically, each of the signals b_{c1} and b_{c2} generated by generator 21 is a binary signal which takes on either a 0 state or a 1 state during each T second interval of the signal b_{if} . The particular state of each of the signals generated by the generator during a given T second interval of b_{if} depends upon whether the interval is in the aforementioned first or second sets of intervals of b_{if} and, therefore, is an odd or even interval and upon whether the state of signal b_{if} has changed from that occurring in the immediately preceding interval. In accord with the invention, if the state of the signal b_{if} in a given interval has not changed from the preceding interval, then the generator 21 causes the signals b_{c1} and b_{c2} to have the same states in the given interval as they had in the preceding interval. Moreover, further in accord with the invention, if the state of the signal b_{if} in a given interval is changed from that of the preceding interval, and if the interval is in the first set of intervals (i.e., is odd), then the generator 21 causes the state of the signal b_{c1} in the given interval to be the same as it was in the preceding interval, while it causes the state of signal b_{c2} in the given interval to be changed from that of the preceding interval. Furthermore, in the case of a change in the state of the signal b_{if} , if the interval is in the second set of intervals (i.e., is even), and not the first set, then the generator 21 causes the state of b_{c2} in the given interval to be the same as it was in the preceding interval, while it causes the state of the signal b_{c1} in the given interval to be changed from that of the preceding interval.

Generator 21 thus responds to the input signal b_{if} by generating the two binary signals b_{c1} and b_{c2} illustrated in FIGS. 5 and 6, respectively. As shown, the 1 state of each of the latter signals is represented by a positive polarity pulse and the 0 state by a negative polarity pulse. Moreover, also as shown, the signals b_{c1} and b_{c2} are assumed to be in their 1 and 0 states, respectively, during the first interval of b_{if} .

Each of the signals b_{c1} and b_{c2} can be observed from FIGS. 4 and 5 to have the same polarity and thus same state in adjacent T second intervals in which the binary signal b_{if} is of the same state (i.e., in the adjacent intervals 3 and 4 and the adjacent intervals 5 and 6). Furthermore, the signal b_{c1} is seen to change state at the beginning of each even interval in which the state of the signal b_{if} is changed from that of the preceding interval (i.e., the intervals 2 and 8), while it is seen not to change state at the beginning of each odd interval. The signal b_{c2} , on the other hand, is seen to change state at the beginning of each odd interval in which the state of the signal b_{if} is changed from that of the preceding (i.e., the intervals 3, 5, and 7), while it is seen not to change state at the beginning of each even interval.

As above-indicated, the signals b_{c1} and b_{c2} control the operation of invert non-invert circuits 16 and 17, respectively. More particularly, application of each of the signals b_{c1} and b_{c2} to its respective invert non-invert circuit causes such circuit to be in its invert mode of operation, if the signal is at a negative polarity (i.e., its 0 state) and in its non-invert mode of operation, if the signal is at a positive polarity (i.e., in its 1 state). The circuit 16 controlled by signal b_{c1} is thus in its invert mode of operation during the T second intervals 2-7 and in its non-invert mode during the T second intervals 1 and 8. The latter circuit, hence, is seen to change modes of operation at the beginning of each even interval in which the signal b_{if} is of a changed state from the

preceding interval. Likewise, the circuit 17 controlled by signal b_{c2} is in its invert mode in the intervals 1, 2, 5, and 6 and in its non-invert mode in the intervals 3, 4, 7 and 8. This circuit thus is caused to switch operating modes at the beginning of each odd interval in which the signal b_{if} is of a changed state from the preceding interval.

As can be appreciated operation of circuits 16 and 17 as aforesaid results in the circuits developing output carrier signals C_c' and C_s' as shown in FIGS. 7 and 8, respectively. More particularly, during each of the T second intervals in which the circuits are in their invert modes of operation, the circuits develop outputs which are the same in amplitude but opposite in polarity to their respective applied carrier signals, while during each of the intervals in which the circuits are in their non-invert modes, the circuits develop outputs which are the same in both amplitude and polarity to their respective applied carrier signals. Thus, as can be observed from FIG. 7, the signal C_c' generated by circuit 16 during the intervals 2-7 is of the same amplitude but of opposite polarity to the applied carrier signal C_c , while during the intervals 1 and 8 the signal C_c' is the same in both amplitude and polarity to the signal C_c . Likewise, from FIG. 8, it can be observed that the signal C_s' generated by circuit 17 during the intervals 1, 2, 5, and 6 is of the same amplitude but of opposite polarity to the applied carrier signals C_s , while during the intervals 3, 4, 7 and 8 the signal C_s' is the same in both amplitude and polarity to the signal C_s . The aforesaid inverted and non-inverted character of each of the signals C_c' and C_s' relative to their applied carrier signals C_c and C_s , respectively, has been indicated in the FIGS. 7 and 8 by designating those intervals where no polarity inversion has occurred by $+C_c$ and $+C_s$, respectively, and by designating those intervals where polarity inversion has occurred by $-C_c$ and $-C_s$, respectively.

As is apparent from the illustrations of the generated carrier signals C_c' and C_s' operation of circuits 16 and 17 in response to control signals b_{c1} and b_{c2} , respectively, has resulted in either the signal C_c' or the signal C_s' comprising an inverted portion of its respective applied carrier signal, during each of the T second intervals in which the signal b_{if} is in its second state (i.e., negative). Thus during the intervals 3, 4, and 7 the signal C_c' comprises a $-C_c$ and the signals C_s' a $=C_s$, while during the interval 1, the signal C_c' comprises a $+C_c$ and the signal C_s' a $-C_s$. As a result, combining of the signals C_c' and C_s' in combiner 22 during the intervals 1, 3, 4 and 7 produces a resultant signal C_r during such intervals which is of the form $\pm(C_c - C_s)$ and which can be readily shown to be a cosinusoidal carrier signal having a second frequency equal to the sum of the carrier frequency f_o and the modulating frequency $\frac{1}{4}T$.

Moreover, it is also apparent from the illustrations of C_c' and C_s' that operation of circuits 16 and 17 has further resulted in both the signals comprising inverted portions or both comprising non-inverted portions of their respective applied carrier signals, during each T second interval in which b_{if} is in its first state (i. e., positive). Thus during interval 8, C_c' and C_s' comprises a $+C_c$ and a $+C_s$, respectively, while during intervals 2, 5, and 6, C_c' and C_s' comprise a $-C_c$ and $-C_s$, respectively. As a result, combining the signals C_c' and C_s' in combiner 22 during these intervals produces a resultant signal C_r which is of the form $\pm(C_c + C_s)$ and which can be readily shown to be a cosinusoidal carrier signal hav-

ing a first frequency equal to the difference between the carrier frequency f_o and modulating frequency $\frac{1}{4}T$.

FIG. 9 shows the aforesaid resultant cosinusoidal carrier signal C_r produced by combiner 22. The particular frequencies taken on by the carrier in each of the T second intervals are designated also. As can be observed, during the intervals 1, 3, 4 and 7 the signal C_r is at a first frequency ($f_o + \frac{1}{4}T$) while during the intervals 2, 5, 6 and 8 the signal is at a frequency ($f_o - \frac{1}{4}T$).

Also noted in FIG. 9, at the beginning of each T second interval, is the phase of the signal C_r relative to that of an unmodulated carrier signal at the carrier frequency f_o . The resultant relative phase change or deviation undergone by C_r during each interval is obtained by subtracting the indicated phase values. Thus, in each of the intervals where the signal C_r is at a frequency ($f_o + \frac{1}{4}T$), the signal undergoes a relative phase change of $+\pi/2$, while in each interval where the signal is at a frequency ($f_o - \frac{1}{4}T$), the signal undergoes a relative phase change or deviation of $-\pi/2$. Hence, the signal C_r undergoes a first phase deviation of $+\pi/2$ in each of the intervals 1, 3, 4 and 7 where b_{if} is in its first state and a second phase deviation of $+\pi/2$ in each of the intervals 2, 5, 6 and 8 in which b_{if} is in its second state. The phase deviations of the signal C_r thus represent the encoded form of the states of the signal b_{if} .

It can be further observed from FIG. 9, moreover, that the signal C_r has a continuous amplitude and, hence, a continuous phase at each transition point marking the beginning of a particular T second interval. This characteristic of the signal C_r comes about from selecting the modulating signals M_c and M_s to have a frequency of $\frac{1}{4}T$ and from the switching circuits 16 and 17 in the above-described manner. More particularly, as above described, since the signals M_s and M_c have frequencies of $\frac{1}{4}T$, the signals C_s and C_c and, hence, the signals C_s' and C_c' are caused to have zero amplitudes at the beginning of the aforementioned first and second sets (i.e., odd and even) intervals, respectively, of b_{if} . As a result, at the beginning of each odd interval, the amplitude of C_c' controls the amplitude of the resultant signal C_r , while, at the beginning of each even interval, the amplitude of C_s' controls the amplitude of the signal C_r . However, since circuit 16, which is generating C_c' by selectively inverting the applied signal C_c , is directed not to change modes of operation at the beginning of each odd interval, the amplitude of the signal C_c' and, hence, the amplitude of the signal C_r , controlled thereby remains continuous at the beginning of each such off interval. Likewise, since the circuit 17, which is generating C_s' by selectively inverting the signal C_s , is directed not to change modes at the beginning of each even interval, the amplitude of the signal C_c' and, hence, the amplitude of C_r , also remains continuous at the beginning of each such even interval.

As can be appreciated from the above, therefore, apparatus 12 has successfully produced a FM-CPSK signal C_r which carries the first and second states of the input binary signal b_{if} via first and second phase deviations.

FIG. 10 illustrates a particular configuration of logic circuits which can be employed for control signal generator 21. Additionally FIG. 10 shows apparatus for performing the functions of invert non-invert circuits 16 and 17.

More particularly, as shown, generator 21 comprises first and second exclusive or circuits 101 and 102, each

of which receives as one of its inputs the binary information signal b_{if} . The circuits 101 and 102 additionally receive as their other inputs, the control signals b_{c1} and b_{c2} developed by flip-flop 103 and 104, respectively. In response to their input signals, the circuits 101 and 102 develop output signals b_1 and b_2 , respectively. The signals b_1 and b_2 , in turn, are applied as inputs to flip-flop circuits 103 and 104, respectively. The flip-flop circuits 103 and 104 are additionally fed control signals $\bar{C}$ and C , respectively. The latter control signal C is generated by a clock signal source 105 which operates in synchronism with the signal b_{if} . The former signal, on the other hand, is derived by passage of the clock signal C through an inverter 106.

The clock signal C generated by source 105 is a binary signal which changes state at the beginning of each interval of b_{if} . Thus, as shown in FIG. 11, the signal C is in a 1 state in the interval 1, a 0 state in the interval 2, etc. Inverter 106 responds to the aforesaid signal C by generating a signal $\bar{C}$ having a state in each interval which is inverted from that of the signal C . Thus, as shown in FIG. 12, the signal $\bar{C}$ has a 0 state in the interval 1, a 1 state in the interval 2, etc.

Each of the flip-flops 103 and 104 is controlled by its respective signal C or $\bar{C}$ in the same manner. In particular, each flip-flop is permitted to respond to a change in the state of its applied signal b_1 or b_2 only when its respective control signal is changing from its 0 state to its 1 state. As a result, flip-flop 103 is only able to respond to a change in its input b_1 at the beginning of each even interval of the signal b_{if} . Likewise, flip-flop 104 is only able to respond to a change in state of its input b_2 at the beginning of each odd interval of the signal b_{if} .

In order to illustrate that the signals b_{c1} and b_{c2} generated by circuit 21 in FIG. 10 conform to the required signals shown in FIGS. 5 and 6, respectively, operation of the circuit will be followed through the first three intervals of the signal b_{if} . More particularly, assuming that the states of the signals in circuit 21 are initially as shown in FIG. 10, the occurrence of 1 state of the signal b_{if} during interval 1 causes no change in the outputs of circuits 101 and 102. As a result, the output of the flip-flop which is permitted to change state at the beginning of this interval, i.e., flip-flop 104, as well as the output of the flip-flop which cannot change state, i.e., flip-flop 103, remain the same. Thus, during interval 1, b_{c1} is maintained at a 1 state and b_{c2} at a 0 state.

At the beginning the interval 2, the signal b_{if} changes from its 1 state to its 0 state. This change is reflected at the inputs to circuits 101 and 102. Since, however, the other input b_{c2} to circuit 101 cannot change state, due to the inability of flip-flop 104 to change state, the 0 state of b_{if} causes the signal b_1 from circuit 101 to change to its 0 state. The aforesaid 0 state of b_1 is received by flip-flop 103 which at this time is able to change state and, hence, does so changing the state of b_{c1} from 1 to 0. Thus, during interval 2, b_{c1} is at a 0 state and b_{c2} is also at a 0 state.

Following the operation of circuit 21 for one more interval, at the start of the third interval, the signal b_{if} again changes state, going from its 0 state to its 1 state. Since, at the start of this interval, b_{c1} cannot change state due to the inability of flip-flop 103 to change state, the 1 state of b_{if} and 0 state of b_{c1} at the input of circuit 102 causes a 1 state output. This output is received by flip-flop 104, which at this time is able to

change state, and does so changing the state of b_{c2} from 0 to 1. Thus, during interval 3 the signal b_{c1} is at a 0 state and the signal b_{c2} is at a 1 state.

As above indicated, also shown in FIG. 10, are the invert non-invert circuits 16 and 17 which receive the signals b_{c1} and b_{c2} , respectively, generated by circuit 21. As illustrated, the circuit 16 and 17 comprise balanced modulators 107 and 108, respectively. Each of the modulators 107 and 108 functions as multiplier and multiplies its respective applied carrier signal by a +1, if its input control signal is in a 1 state, and by a -1 if its control signal is in a 0 state. As is apparent such operation of modulators 101 and 108 will result in the generation of the signals C_{c1}' and C_{c2}' illustrated in FIGS. 7 and 8, respectively.

As can be noted from the above discussion of FIGS. 1 and 10, apparatus 12 does not employ any circuitry which must be switched in operation in a time less than the time T occupied by each state of binary signal b_{if} . As a result, it is found that apparatus 12 is capable of encoding binary signals having high bit rates, i.e., bit rates of the order of 1 Mb/s.

In all cases, it is understood that the above-described arrangements are merely illustrative of the many possible specific embodiments which represent applications of the present invention. Numerous and other varied arrangements can be readily devised in accordance with the principles of the present invention without departing from the spirit and scope of the invention.

What is claimed is:

1. Apparatus for encoding a binary signal having a pulse period T into a frequency-modulated coherent phase-shift keyed signal, which comprises:
  - means for generating an amplitude-modulated, sinusoidal carrier wave of frequency f_o , the signal modulating said carrier wave comprising a sinusoidal wave of frequency $\frac{1}{4}T$;
  - means for generating an amplitude-modulated, sinusoidal carrier wave of frequency f_o , the signal modulating said carrier wave comprising a sinusoidal wave of frequency $\frac{1}{4}T$;
  - means, responsive to said binary signal, for generating first and second binary control signals, the logical value of said first binary control signal being changed if, and only if, a change in the logical value of the binary signal to be encoded occurs at the beginning of alternate time slots in said binary signal, the logical value of said second binary control signal being changed if, and only if, a change in the logical value of the binary signal to be encoded occurs at the beginning of the remaining time slots in said binary signal, said first and second binary control signals initially having opposite logical values;
  - means for combining the output of said sinusoidal wave generating means with the output of said sinusoidal wave generating means;
  - means, interposed between said combining means and said sinusoidal wave generating means and responsive to said first binary control signal, for selectively inverting said sinusoidal carrier wave; and
  - means, interposed between said combining means and said sinusoidal wave generating means and responsive to said second binary control signal, for selectively inverting said sinusoidal carrier wave, whereby the output of said combining means comprises the desired phase-shift keyed signal, which

signal selectively assumes the frequency ($f_o + \frac{1}{4}T$) or ($f_o - \frac{1}{4}T$) depending upon the instantaneous logical value of the binary signal to be encoded.

2. The apparatus according to claim 1 wherein f_o , the frequency of both said cosinusoidal and said sinusoidal carrier wave, is harmonically related to the frequency $1/T$.

3. The apparatus according to claim 1 wherein said cosinusoidal and sinusoidal wave inverting means comprises a balanced modulator.

4. The apparatus according to claim 1 wherein said means for generating said first and second binary control signals comprises:

a first logic circuit whose output signal comprises said first binary control signal;

a second logic circuit whose output signal comprises said second binary control signal;

a third logic circuit responsive to said first binary control signal and to said binary signal for developing an output signal which has two states and which

10

15

20

changes state as a function of changes in state of said first binary control signal and said binary signal;

a fourth logic circuit responsive to said second binary control signal and to said binary signal for developing an output signal which has two states and which changes state as a function of changes in state of said second control signal and said binary signal;

means for applying the output signal from said third logic circuit to said first logic circuit;

means for applying the output signal from said fourth logic circuit to said second logic circuit;

a clock circuit synchronized with said binary signal, the output of said clock circuit being connected to said first and second logic circuits; and

means interposed between said clock circuit and said first logic circuit for inverting the polarity of the clock pulses from said clock circuit.
